Application May 13, 1940, Serial No. 334,734

3 Claims. (Cl. 103—53)

This invention relates to fluid pumps and in particular to fluid pumps of electro-magnetic type.

Fluid pumps of the prior art, which are particularly adapted for application where a relatively small capacity discharge is required, are usually bulky in size and expensive in cost and operate efficiently with only relatively low suction lifts. These prior art pumps generally include a diaphragm or bellows for producing the pumping action and are limited in duration of service by the fatigue limits of the diaphragm material, and in their effective pumping head by the tension or spring characteristics of the diaphragm. Since the amplitude of diaphragm deflection determines the pumping stroke, the diaphragm is relatively large with respect to the pump fluid passages to provide for a desired pump capacity with a minimum deflection of the diaphragm. The life of the diaphragm is thus increased, but the bulk of the pump is also increased. In addition the control valves for regulating the flow of the fluid through the pump are usually arranged at some distance from the pumping chamber to increase further the bulk of the pump and hence the difficulties of its assembly in close quarters.

These disadvantages of the diaphragm pumps have been overcome to some extent by the use of electro-magnetically operated piston-type pumps. Commercially available piston-type pumps and the piston pumps of the prior art, however, include pumping chambers and control valves which are usually arranged about and at some distance from the operating solenoid. The small capacity piston-type pumps now generally used are, therefore, rather complicated in design, bulky in size, and expensive in cost and thus fail to satisfactorily eliminate the chief disadvantages of the diaphragm pump.

An object of this invention, therefore, is to provide an improved pump of electro-magnetic type.

It is a further object of this invention to provide an electro-magnetic pump having a variable discharge.

Yet another object of this invention is to provide a reciprocating pump of electro-magnetic type which is of compact design, cheap in cost, and efficient in operation.

It is a further object of this invention to provide a solenoid actuated fuel pump for an internal combustion device having a fuel system and an ignition system, in which the solenoid is op-

eratively arranged to effect an energization of the ignition means in the ignition system.

A feature of this invention is the provision of a reciprocating fuel pump in which the piston is operable in a cylinder having a bore substantially equal to the diameter of the pump inlet and outlet passages, and is actuated for movement in one direction by resilient means arranged in compression and located in said cylinder whereby to provide for a relatively high effective operating pressure of the piston.

Another feature of this invention is the provision of a reciprocating pump having a tubular cylinder with a control valve at each end and with an elongated piston operable therein substantially between the cylinder ends, the piston being formed with a longitudinal fluid passage therein having a control valve near one of its ends, and all three of the control valves being adapted for opening in the direction of fluid flow through the pump and operable in response to the fluid pressures in said cylinder to provide for a pumping action of the pump through the passage in the piston.

Yet another feature of this invention is the provision of a reciprocating pump in which the piston is of elongated construction and operatively associated with a pumping chamber of tubular form, comprising a portion of the fluid supply line and having a fluid inlet at one end and a fluid outlet at the opposite end, the fluid from the inlet passing to the outlet through a longitudinal opening formed in the piston and the piston being self-lubricated by its complete immersion in the fluid passage through the pump.

Further objects, features and advantages of this invention will be apparent from the following description when taken in connection with the accompanying drawings wherein:

Fig. 1 is a longitudinal sectional elevation of one form of the invention;

Fig. 2 is a sectional view taken along line 2—2 in Fig. 1;

Fig. 3 is a longitudinal elevational view, partly in section, of a modified embodiment of the invention;

Fig. 4 illustrates diagrammatically an electrical circuit for the embodiments of Figs. 1 and 3;

Fig. 5 is a fragmentary sectional view of a check valve structure which may be used in the embodiments of Figs. 1 and 3; and

Fig. 6 illustrates diagrammatically an electrical operating circuit for the embodiments of

Figs. 1 and 3 when used in the ignition system for an internal combustion device.

With reference to the drawings similar characters of reference shall designate similar parts throughout the several views. In Fig. 1 there is shown a reciprocating pump including a cylinder 10 of tubular form which is operatively associated with a piston 11 of elongated construction. The cylinder or sleeve 10 is provided in a suitable non-magnetic material, such as die cast or brass, while the piston is provided in a magnetic material, such as iron, movement of the piston in one direction being effected on energization of the solenoid 12 which is mounted about the sleeve 10; the piston 11 operating as a solenoidal core. Fluid enters the pump at the cylinder end 13 and is discharged therefrom at the cylinder end 14, the piston being operable substantially between the cylinder ends. The piston 11 is formed with a longitudinally extending passage 16 of reduced section and an enlarged passage section or annular recess 17 which is in register with the passage 16 and located at the piston end 18, which is near the inlet end 13 of the cylinder 10, the recess 17 having a valve structure 19 located therein, which is operable to control the flow of the fluid through the passage 16. The inner end of the recess 17 is formed with an annular groove 22 which extends in spaced relation about the passage 16 to form an annular longitudinally extending flange 23, the flange being provided with a plurality of apertures 26 to connect the groove 22 and the passage 16, for a purpose to be later described.

The valve structure 19 located in the recess 17 includes a disc member 27 (Figs. 1 and 2) which is adapted to fit over the passage 16 and is held in the recess 17 by a plug 29 having a bore 31 therein of a diameter commensurate with the diameter of the passage 16, the inner end of the plug being formed with a reduced section 32 to provide an annular seat 33 for the disc valve 27. The disc 27 is thus longitudinally movable between the end 24 of the flange 23 and the annular seat 33 at the inner end of the plug 29. A spring 34 positioned in the groove 22 and arranged in compression between the disc 27 and the bottom of the groove serves to retain the disc 27 on its seat 33. Since the efficient operation of the disc 27 is dependent upon a positive seating of the disc on the seat 33, the distance between the seat 33 and the flange end 24 is very small and equal to about twice the thickness of the disc 27, to reduce to a minimum any tilting or canting of the disc when it is raised from its seat 33. In some cases, however, it may happen that the disc 27 will be urged into seating engagement with the flange end 24, since this condition would effect a closing of the passage 16, the disc is formed with notches 36 in the peripheral edge thereof so that communication between the passages 31 and 16 will occur through the apertures 26, groove 22 and notches 36. A positive flow of fluid through the passages 31 and 16 is thus assured for any position of the disc 27 from its seated position on the seat 33.

Suitably secured to the inlet end 13 of the cylinder 10 is a head or valve body member 37 which is formed with a passage 38 of reduced section and a recess 39 of enlarged section, which are in register with each other and with the pump inlet chamber 41 in the cylinder 10. The inner end of the recess 39 is formed with an annular groove 42 which extends in spaced relation about the inner end 45 of the passage 38 to provide an annular

seat 43 for a disc 44, which is operable to control the flow of the fluid through the passage 38. The disc 44 is normally maintained in seating engagement with the annular seat 43 by a spring 46, which is arranged in compression between the disc 44 and a shoulder 47 formed on a plug member 48, the plug member 48 being threadably secured in the recess 39. The plug 48 is formed with a passage 49 which corresponds in diameter with the passages 31 and 38, the wall portion near the inner end 50 of the passage 49 being formed with apertures 51, to provide for communication between the passages 38 and 49 through the spring recess 52 and the notches 53 formed in the peripheral edge of the disc 44 in the event the disc should become seated on the plug end 50, the structure and operation of the disc 44 being similar to that of the disc 27 just described.

A head or valve body member 54 is suitably secured to the outlet end 14 of the cylinder 10 and is formed with a passage 56 of reduced section and a recess 57 of enlarged section, the passage 56 being arranged for alignment with the passage 16 in the piston 11. The inner end of the recess 57 is provided with an annular groove 58 which extends in a spaced relation about the passage 56 to form an annular seat 59 at the passage end 61. A disc 62, similar to the discs 27 and 44 previously described, is normally maintained in seating engagement on the seat 59 by a compression spring 63 which is held in the recess 57 by a plug member 64, the member 64 being formed with a passage 66 therethrough which corresponds in size with the passages 16 and 56. Also, similarly to the discs 27 and 44, the disc 62 is formed with peripheral notches 67 to provide for a flow of fluid therethrough and through the spring groove 68 and apertures 69, in the event of its seating on the end 60 of the passage 66. All of the discs 27, 44, and 62 are thus adapted to be of a diameter substantially equal to that of the fluid passages in the pump and may be provided in a phenolic or resinous composition material, which is of light weight and impervious to the action of gasoline or the like, to facilitate their being moved at relatively low operating pressures.

In the operation of the pump the piston 10, as previously described, is moved in one direction, namely, to the left as viewed in Fig. 1 by the magnetic action of the solenoid 12. A return movement of the piston 10, towards the right, is obtained by a spring 11 which is located in the inlet chamber 41 and arranged in compression between the piston end 18 and the valve body member 37. As shown in Fig. 4, the solenoid 12 is selectively energized by an energizing circuit which includes a battery 72 connected in series with the solenoid 12 through contact arms 73, contact between the arms 73 being effected by the operation of a cam 74 which in the case of the pump being employed in the fuel system of an internal combustion engine may be mounted on the engine cam shaft. In the application of the pump for use in a heater of internal combustion type the cam 74 may be mounted on the shaft of a motor for the air circulating or air supply fans. On closing of the contacts 73 the piston 11 is moved to the left, which movement effects a reduction in the size of the chamber 41 and a consequent increase in the pressure of the fluid in such chamber, the increased pressure acting to seat the disc 44 on its seat 43 whereby to prevent any flow of fluid outward from the pump

through the passage 38 and acting further to force the disc 27 from its seat 33 to provide for a flow of the fluid from the chamber 41, through through the passages 31 and 16 into the expanding outlet chamber 76 which is formed at the cylinder end 14, as indicated by the dotted lines 77. The chambers 41 and 76, when fully expanded, are of substantially the same size so that the fluid pressure in the chamber 76 is substantially equal to the fluid pressure in the chamber 41 prior to its reduction by movement of the piston 10. Since this pressure is on the order of the pressure in the fuel supply line and hence in the passage 38, as will be later explained, a relatively low pressure exerted by the spring 68 is sufficient to maintain the disc 62 on its seat 59; the springs 34 and 52 being substantially similar to spring 68. Immediately upon opening of the contacts 73, by the continued rotation of the cam 74, the solenoid 12 is de-energized and the spring 71 acts to force the piston 10 towards the right. This movement of the piston 10 produces a suction pressure in the inlet chamber 41, due to its being expanded, whereby the disc 44 is opened to provide for a flow of fluid through the passages 38 and 49 into the inlet chamber 41; the fluid admitted to the chamber 41 being at substantially supply line pressure. The fluid in the outlet chamber 76 is compressed due to such chamber being contracted, this increase in pressure providing for a closing of the disc 27 and for an opening of the disc 62 whereby the fluid under pressure is discharged from the pump through the passages 56 and 66. Upon a reclosing of the contacts 73 the solenoid 12 is again energized and the cycle of the piston 10 is repeated.

It is thus seen that the disc valves 44, 27 and 62 all open in the direction of fluid flow and are operable in response to the fluid pressures produced in the reducible and expandable chambers 41 and 76, by the reciprocating action of the piston 11 in the cylinder 10. This arrangement of the valves provides for a successive moving of the fluid through the pump, the fluid first being admitted into the inlet chamber 41 through the passages 38 and 49 on movement of the piston 11 toward the right, then passed through the passages 31 and 16 in the piston 11 to the chamber 76 on movement of the piston 11 toward the left, and finally ejected from the pump, and specifically from the outlet chamber 76, through the passages 61 and 66 on movement of the piston 11 toward the right. It is to be noted that the movement of the piston 11 toward the right provides for the drawing of fluid into the chamber 41 through the valve 44, and the discharge of the fluid from the chamber 76 through the valve 62, so that the suction action of the pump occurs concurrently with its ejection action.

The diameter of the bore of cylinder 10 is of a size sufficient to provide for a piston 11 having passages 31 and 16 which correspond in diameter with the passages 38 and 66, which represent substantially, the diameter of the fluid supply line (not shown), which is adapted for connection to the head members 37 and 54. The size of the pump is thus reduced to a minimum, and the arrangement of the valves and piston to provide for an entire pumping action in the cylinder 10, provides for a pump having a pump chamber which is formed as a part of the fuel supply line. The location of the piston 11 in the fluid supply line portion formed by the cylinder 10, effects a continuous lubrication of the elongated piston 11 to provide for its free operation in the cylinder 10. Location of the spring 71 within the cyl-

inder 10 provides for the full effective spring pressure being utilized in operating the piston 11 so that a high maximum fluid pressure is produced in the discharge passage 66. That is, the spring pressure exerted by the spring 71 is distributed only over the piston sectional area, and since this area is relatively small, being of the order of about $\frac{1}{16}$ of a square inch, a spring pressure of only about 1 pound per square inch will effect a pump operating pressure of about 10 pounds per square inch. This feature of the present invention provides for a pump of small capacity which is adapted to operate efficiently with high suction lifts, and the pump, therefore, may be arranged or assembled over a wide range of positions in the particular fluid system in which it is employed.

In the reciprocating movement of the piston 11 in the cylinder 10 the spring 71 operates to move the piston to the right a distance about equal to the movement of the piston to the left as imparted by the action of the solenoid 12. Any variation, therefore, in the leftward travel of the piston 11 will provide a corresponding variation in the movement of the piston toward the right. Since the solenoid 12, on energization thereof, acts to draw or attract the iron piston 11 inwardly of the non-magnetic sleeve or cylinder 10 to a neutral position, which occurs when the piston end 78 is substantially flush with the solenoid end 19, a movement of the solenoid on the cylinder 10 toward the right will effect a shorter operating stroke of the piston 11; a maximum stroke being effected when the solenoid is positioned at the cylinder end 13. A variable pump capacity is thus obtained by adjusting or moving the solenoid 12 relative to the cylinder 10; a desired adjustment being maintained by adjusting nuts 81 which are arranged at opposite ends of the solenoid 12.

In some installations, such as gravity feed systems, the fuel in the supply line may be subjected to varying pressures and to pressures which are in excess of the pressures normally exerted by the valve springs 52, 34, and 68 on the discs 44, 27, and 62, respectively, so that when the pump is not operating this pressure might be sufficiently high to open or crack the valves 44, 27 and 62 and thus provide for a flow of fuel through the pump. To eliminate any such occurrence of fuel leakage through the pump the piston 11' (Fig. 5) may be formed at its discharge end 78' with a valve portion 82, which is adapted for seating engagement with a valve seat 83 formed at the inner end of the passage 56' in the head or valve body member 54'. Seating of the valve portion 82 in the valve seat 83 occurs at the extreme end of the discharge stroke of the piston as effected by the spring 71. Fuel communication between the passages 16' and 56' during normal operation of the pump is obtained through apertures 84, which are formed in the valve portion 82 and are located in such portion so as to be closed by the seating engagement of the portion 82 in the valve seat 83. During operation of the pump, therefore, the pump discharge action is stopped upon the engagement of the piston 11' in the head member 54', so that the check or lock-out valve 82-83 functions as a discharge cutoff. When the pump is not in operation the engagement of the valve portion 82 with the valve seat 83 is maintained by the pressure of the spring 71, so that any additional pressure in the fuel supply line above the pressure exerted by the spring 71, serves only to

further maintain this seating engagement rather than to effect a release of such engagement. Any leakage of fuel through the pump, at such times when it is not in operation, is thus positively prevented.

The embodiment of Fig. 3 includes a cylinder 10, a piston 86 and a solenoid 12 mounted about the cylinder 10. The piston 86, as viewed in Fig. 3 is adapted to be moved to the right by the solenoid 12 so that discharge of the fluid from the pump is effected by the action of the solenoid 12, rather than by the spring 11'. This reversed actuation of the piston 86 by the solenoid 12, as compared to the movement of the piston 11 in Fig. 1 is accomplished by positioning the solenoid at the end 14 of the cylinder 10, the drawing of the piston 86 to a neutral position within the solenoid being effected in an opposite direction. The stroke of the piston, therefore, is decreased by moving the solenoid to the left on the cylinder 10. The spring 11' is also located at the cylinder end 14 and the pressure exerted by the spring acts to move the piston 86 toward the left. An inlet head member 87 is secured to the cylinder end 13 and is formed with a fluid passage 88 which is in alignment with the fluid passage 89 formed in the piston 86. The flow of the fluid through the passages 88 and 89 is controlled by check valves 91 and 92, respectively, which are of the usual type; the valves 91 and 92 being operable in response to the fluid pressures occurring in the cylinder 10 and arranged to open in the direction of fluid flow through the pump. An outlet head member 93 is secured to the cylinder end 14 and is provided with a passage 94 which is illustrated as being in communication with the outlet chamber 16' and in alignment with the passage 89 in piston 86, the flow of the fluid through passages 94 being controlled by a check valve 96 which is similar to the valves 91 and 92 and also adapted for opening in the direction of fluid flow through the pump.

The operation of the embodiment of Fig. 3 is similar to that previously explained in connection with Fig. 1; the circuit in Fig. 4 also being applicable to Fig. 3. On energization of the solenoid 12 the piston 86 is moved to the right whereby fuel is drawn through the passage 88 into the inlet chamber 41' concurrently with the discharge of fuel through the passage 94 from the outlet chamber 16'. On de-energization of the solenoid 12 the piston 86 is moved to the left by the pressure of spring 11' to transfer the fluid from the chamber 41' through the piston passage 89 into the outlet chamber 16'. When the solenoid 12 is again energized the cycle of operation is repeated.

In the employment of the invention with internal combustion devices having both a fuel feeding system and an ignition system, such as an automobile heater or automobile engine, the solenoid 12 may be used to operate effectively as a primary winding to provide an operating voltage for the ignition means included in the usual ignition system. This application of the invention is schematically illustrated in Fig. 6, in which the solenoid 12 is mounted about the cylinder 10 and in operative association with a secondary winding 97, the winding 97 being shown as extending about the solenoid 12. Assuming the cylinder 10 and solenoid 12 to include the structure of Fig. 1, in which the piston 11 is moved to the left on energization of the solenoid 12, closing of the contacts 13' by the cam 14' permits current to flow from the battery

72' through conductor 98, contacts 13' and conductor 99 to the solenoid 12, the circuit being completed by the ground connection 101. As previously explained, this energization of the solenoid 12 moves the piston 11 to the left, which movement effects a compression of the spring 11. On opening of the solenoid circuit by an opening of the contacts 13' the solenoid 12 is de-energized, the collapse of the current flow therein effecting a voltage increase in the secondary winding 97, in the usual manner, which is adapted to effect a spark across the gap 104, the secondary circuit upon opening of the contacts 13' being comprised from the battery 12' of conductor 98, condenser 106, conductors 99 and 102, conductor 103, spark gap 104 and ground connection 106. Since de-energization of the solenoid 12 occurs prior to the movement of the piston 10 toward the right by the spring 11, the spark will occur at the gap 104 before the ejection of the fuel from the outlet passage 66. The spark thus occurs in advance of the fuel discharge. In the application of the pump to an automobile heater the advance of the spark relative to the fuel discharge does not interfere with the operation of the heater since a relatively timed occurrence of the fuel and spark in the heater combustion chamber is not essential to its efficient operation.

However, in the operation of an internal combustion engine, a more efficient operation of the engine is obtained by a spark which lags or follows after the fuel admission into the engine, since the admission of the fuel and occurrence of the spark in the usual engine cylinder is relatively timed to correspond with a predetermined operating position of the engine piston. The occurrence of a fuel discharge prior to the occurrence of a spark is obtained by the embodiment of Fig. 3, the circuit of Fig. 6 remaining the same. Thus on energization of the solenoid 12 the piston 86 is moved toward the right to discharge the fluid from the outlet chamber 16' through the passage 94 prior to an opening of the solenoid circuit. Since the solenoid circuit remains closed until after the fuel has been ejected from the pump, the spark at the gap 104 is thus timed to lag the admission of fuel to the engine.

The invention is thus seen to provide for a fluid pump which is of rugged construction, simple and compact in design, and adapted for efficient operation with relatively high suction lifts. The pumping action of the fluid through the pump is controlled by an arrangement of valves which require a minimum of adjustment and replacement and which act positively at all times during pump operation. The pump chamber is formed as a part of the fuel supply line so that the pump may be arranged anywhere along the length of the supply line between the fuel source and the point of desired fuel discharge. A complete immersion of the pump piston in the fuel line provides for a self-lubricated piston, so that the piston is freely movable at all times. The invention further provides an electro-magnetic pump in which the solenoid may be utilized as a primary winding in the operation of internal combustion devices which employ both a fuel system and an ignition system, the solenoid being operatively associated with a secondary winding for the ignition means included in the ignition system, to provide for a voltage increase in the secondary winding on a collapse of the current in the solenoid on de-

energization thereof. The assembly of the solenoid directly about the pump chamber or cylinder and the operation of the pump piston as a solenoidal core within the pumping chamber, provides a ready means for varying the capacity of the pump, so that a variable discharge is readily obtained. The pumping action is such as to completely evacuate all fluid mixtures which might be admitted thereto so that air binding, with the consequent provision of air release valves or domes, is entirely eliminated through the normal operation of the pump.

It is to be understood that only preferred embodiments of the present invention have been described and illustrated herein and that alterations and modifications thereof can be made which are within the full intended scope of the invention as defined by the appended claims.

I claim:

1. In a fluid pump including a cylinder having a fluid inlet and a fluid outlet with said inlet connected to a fluid supply line, the combination of an elongated piston operatively associated with said cylinder and movable therein substantially between said inlet and outlet, said piston being of tubular construction and closed at one end, with the bore in said piston serving as a fluid passage and said one end being formed with a valve portion having apertures therein opening into said piston fluid passage, a body member connected to said cylinder at said outlet having a fluid discharge passage therein communicating with said piston fluid passage through said apertures, valve means in said piston for controlling the flow of fluid through said piston passage, valve means at said cylinder inlet and outlet for controlling the flow of fluid through said cylinder, all of said valve means being arranged to open in the direction of fluid flow through said cylinder and to operate in response to the fluid pressure produced in said cylinder by the reciprocating

action of said piston to provide for a successive flow of the fluid through said cylinder inlet, piston passage, cylinder outlet, and discharge passage, and means including said piston valve portion for preventing a flow of fluid through said cylinder when said pump is not operating, said body member having a valve seat thereon engageable with said valve portion when said piston is at one limit of its reciprocatory travel to close said apertures, with an increase of the fluid pressure in said supply line acting to urge said valve portion against its seat.

2. In a fluid pump including a tubular cylinder having an inlet at one end and an outlet at the other end, and a tubular valved solenoidal core reciprocally movable within said cylinder between the ends thereof for drawing fluid through said inlet and discharging it through said outlet, the combination of means for reciprocating said core in said cylinder including a solenoid adjustably mounted about said cylinder, and means operatively connected with said cylinder and solenoid for adjustably moving said solenoid axially of said cylinder to vary the reciprocating movement of said core.

3. In a fluid pump, the combination of a non-magnetic tubular cylinder having a magnetic piston of elongated construction operatively associated therewith and slidable substantially between the ends thereof, a solenoid slidably mounted on said cylinder and adapted on energization thereof to actuate said piston, said cylinder having a threaded end portion, and means for adjusting the working stroke of said piston including an adjustable member threadably connected with said threaded end portion for movement axially of said cylinder, said adjustable member being operatively engageable with said solenoid to slidably move the same axially of said cylinder to adjust said piston stroke.

HARRY B. HOLTHOUSE.
